SHADE FOR A LAMP

Bozidar M. von Serda, 9304 Santa Monica Blvd.,
Beverly Hills, Calif. 90210

Filed Aug. 26, 1974, Ser. No. 500,324

Term of patent 14 years

Int. Cl. D26—05

U.S. Cl. D48—16 D

Fig. 1

Fig. 3

FIG. 1 is a perspective view of a shade for a lamp showing my new design;

FIG. 2 is a side elevation taken in the direction of the arrow 2 in FIG. 1; and

FIG. 3 is a top plan.

The bottom appears as a mirror image of the top. I claim:

The ornamental design for a shade for a lamp, substantially as shown and described.
